UNITED STATES PATENT OFFICE.

FREDERICK SIFFERMAN, OF SOUTH BETHLEHEM, PENNSYLVANIA.

AIRSHIP.

1,077,004.

Specification of Letters Patent.

Patented Oct. 28, 1913.

Application filed October 8, 1912. Serial No. 726,579.

To all whom it may concern:

Be it known that I, FREDERICK SIFFERMAN, a citizen of the United States, residing at South Bethlehem, in the county of Northampton and State of Pennsylvania, have invented new and useful Improvements in Airships, of which the following is a specification.

This invention relates to airships, and its main object is to obviate the use of supporting planes or balloons and to provide a construction wherein rotary propellers operate both to support and propel the ship, as well as to enable its altitude to be varied.

15 A further object of the invention is to provide a construction and arrangement of propellers whereby a gyroscopic action is established to maintain stability.

A still further object of the invention is 20 to provide means coöperating with the propellers to support the ship and increase the sustaining action of the propellers, as well as to serve as a parachute to control the speed of descent of the ship.

25 A still further object of the invention is to provide a compact type of airship which will develop great lifting power and speed.

With the above and other objects in view, the invention consists of the features of construction, combination and arrangement of parts hereinafter fully described and claimed, reference being had to the accompanying drawings, in which:—

Figure 1 is a slide elevation, partly in section, of an airship embodying my invention. Fig. 2 is a front elevation of the same. Fig. 3 is a top plan view of the airship. Fig. 4 is a vertical section along the longitudinal axis of the ship. Fig. 5 is a vertical transverse section on line 5—5 of Fig. 4. Fig. 6 is a detail view of one of the rotary cylinders. Fig. 7 is a detail view of one of the spiral blades thereon.

The body or frame of my improved airship comprises front and rear cylindrical body sections 1 and 2, the former having a suitably tapered or streamline bow 3, said sections 1 and 2 including rings or bands 4 and 5, respectively from which extend series 45 of arms 6 and 7, intermediate which is a third series of arms 8. The respective series of arms 6, 7 and 8 extend on a semicircle upwardly from horizontal lines at the opposite sides of the body and support a sustaining surface 9, which is correspondingly

shaped and is composed of a frame structure covered with fabric or other suitable material. The body section 1 forms a car or cabin in which the aviator's seat 10, driving motor 11 and the steering and controlling devices are arranged, and between this section 1 and the rear section 2 and completing the formation of the body structure are front and rear rotary cylinders 12 and 13. In general each of the said sections of the frame consists of a central hub 14, a rim 15 and an interconnecting series of braces 16 which may be of any preferred construction, together with a fabric or other covering 16'.

Extending longitudinally through the body in line with its axis is a main driving shaft 17 which is journaled in suitable anti-friction bearings 18 carried by the front and rear body sections and the central set of frame arms 8. The front rotary cylinder 12 is secured to a hollow shaft 19 which turns upon anti-friction bearings 20 interposed between the same and the shaft 17, to which shaft 17 the rear rotary cylinder 13 is fixed 70 for rotation therewith. The two cylinders 12 and 13 carry annular series of spiral propeller blades 21 and 22 which are adapted to exert both a lifting and propelling action on the air, and to force the air against 75 the sustaining surface 9 to augment the sustaining action and lifting capacity of the ship. The two propeller cylinders rotate at uniform speeds in opposite directions and thus tend by their gyroscopic action to maintain a fixed direction of flight and to thus constantly keep the ship in a state of poise or equilibrium. Through the medium of the cylinders 12 and 13 and their propeller blades 21 and 22, the ship may be launched 80 directly from the ground and its speed of descent regulated.

In the event of danger, however, such as caused by the stoppage of the motor or fall of the machine from any other cause, the surface 9 will perform the 85 function of a parachute to regulate its speed of descent and enable the aviator to regain control. As shown, the surface 9 is curved fore and aft to a desired degree and of semi-circular form transversely, adapting it to 90 serve both the function of a supporting surface and a safety parachute.

In the operation of each set of lifting and sustaining propellers, the air forced upwardly by the propellers is compacted and 95

compressed against the sustaining surface and then discharging in a lateral direction, the counteracting air pressures from the two sets of propellers tends to maintain lateral equilibrium.

The forward end of the shaft 17 supports a hollow shaft 23 which turns in contact with anti-friction bearings 23' and carries a driving propeller 23^a. Fixed respectively to said shaft 17 and the shaft 19 are beveled gears 24 and 25 which receive motion from a gear 26 driven from the motor 11, whereby the shaft 17 and propeller cylinder 12 are rotated in one direction, while the propeller cylinder 12 is rotated at a like speed in the opposite direction. Fixed to the shaft 23 is a beveled gear 24^a meshing with a similar gear 26^a driven from the motor 11, whereby the propeller 23^a is driven, the gearing being such as to revolve the said propeller 23^a at a higher rate of speed than the propellers 12 and 13. To the rear body section 13 is hinged or pivoted a vertical rudder 27, which is operated by cords or other suitable connections 28 from a control device 29 in the car or cabin. Horizontal Rudders 30 are mounted upon shafts 31 extending through and journaled in the lower horizontal arms 6, which are made hollow for the purpose and said shafts are coupled at their inner ends and provided with oppositely extending crank arms 32 and 33 connected by ropes or cables 34 with a control device 35 in the car or cabin. The vertical and horizontal rudders may, therefore, be conveniently adjusted to respectively steer the ship horizontally and vertically, while the horizontal rudders may also be adjusted to maintain longitudinal equilibrium. The front and rear sections have suitable brackets 36 and 37 depending therefrom and supporting front and rear sets of cushioned wheels 38 and 39, whereby the ship may be supported upon the ground and launched and landed without excessive shocks or jars. As shown, the shaft 17 is hollow and forms a conductor for the feed of fuel from a supply tank 40, housed in the cylindrical section 2, to a pipe 41 leading to the motor 11, which pipe 41 is provided with a controlling valve 42.

From the foregoing description, it will be seen that my invention provides an airship which combines principles of the aeroplane and helicopter, but in which the helicopter screws are horizontally disposed and form a part of the body of the machine and in which said screws rotate in vertical planes and force the air displaced thereby against

the sustaining surface 9, so as to increase the lifting capacity of the ship.

Other advantages of the invention will be apparent from the foregoing description.

I. claim:—

1. A flying machine including a body 65 formed of front and rear stationary sections and a pair of intervening rotary cylinders, a shaft extending longitudinally through the body and to which one of said cylinders is fixed, a second shaft journaled on the first 70 named shaft and carrying the other cylinder, propeller blades upon the respective cylinders, a driving propeller activated by the first named shaft, means for oppositely rotating the shafts, arms extending from the 75 body, and an arched sustaining surface arranged above the body and supported by said arms.

2. A flying machine comprising an elongated hollow body, including front and rear 80 stationary sections and a pair of intervening rotary cylinders, a shaft extending longitudinally through the body and to which one of said cylinders is fixed, a second shaft journaled on the first named shaft and carrying another cylinder, a third shaft journaled on the first named shaft and carrying 85 a driving propeller, a motor, gearing between the motor and two first named shafts for driving said shafts in opposite directions, gearing between the motor and third shaft, and spiral propeller blades upon the 90 rotary cylinders.

3. A flying machine including an elongated hollow body comprising front and 95 rear stationary sections and a pair of intervening rotary cylinders, a shaft extending longitudinally through the body and to which one of said cylinders is fixed, a second shaft journaled on the first named shaft and 100 carrying the other cylinder, propeller blades upon the rotary cylinders, a driving propeller at the forward end of the body, a third shaft journaled on the first named shaft and carrying said propeller, a motor driven 105 means within the front section of the body for driving the third shaft and for rotating the two first named shafts in opposite directions, arms extending from the body, and an arched sustaining surface arranged above 110 the body and supported by said arms.

In testimony whereof I affix my signature in presence of two witnesses.

FREDERICK SIFFERMAN.
